ATTORNEY:

UNITED STATES PATENT OFFICE.

WILLIAM J. FERGUSON, OF BALTIMORE, MARYLAND, ASSIGNOR OF ONE-HALF TO WILLIAM G. H. STUMP, OF SAME PLACE.

LUBRICATOR.

SPECIFICATION forming part of Letters Patent No. 542,957, dated July 16, 1895.

Application filed April 11, 1895. Serial No. 545,356. (No model.)

To all whom it may concern:

Be it known that I, WILLIAM J. FERGUSON, a citizen of the United States, residing at Baltimore, in the State of Maryland, have invented certain new and useful Improvements 5 in Lubricators, of which the following is a specification.

This invention relates to an improvement in lubricators of that type in which a spring-pressed plunger is employed within the lubricant-receptacle to force the oil or grease therefrom.

The object is to provide a lubricator of the class described having certain improved construction of parts, as will be hereinafter described and set forth in the appended claim.

In the accompanying drawings, illustrating the invention, Figure 1 is a side elevation of the lubricator. Fig. 2 is a central vertical 20 section of the same. Fig. 3 is a vertical section of the cap and spring-pressed plunger as seen when detached. Fig. 4 is a top or plan view of the lubricator with the plunger-stem above the top in cross-section. Fig. 5 is a bottom view of the outlet screw-plug. Fig. 6 shows two views of the valve-locking parts.

In the accompanying drawings, A designates the cylindric cup or receptacle to contain the grease or oil lubricant, provided at its lower end with an exteriorly screw-threaded nipple or boss B, through which extends the outlet-passage b. This boss has a bore c, which extends crosswise of the said outlet-passage b, and a plug-valve d fits snugly in the bore and has a port d', and controls the passage of the lubricant through the outlet-passage. By this construction and arrangement the valve has three operative positions; 30 first, one in which its port d' is fully coincident with the outlet-passage b, and said passage is full open to its fullest capacity for outflow of the lubricant; second, another in which the port d' is partially coincident with the outlet-passage, so as to partially cut off the flow of the lubricant, and, third, another in which the valve-stem is turned so that its port d' will be closed and will entirely cut off the flow of lubricant through the outlet-passage. A locking device to hold the valve 40 at each of said three positions is provided.

The valve-stem has at its free end a rigid arm or projection e, which has a slot e', and a plate-spring f is confined by a screw f' and has a pointed prong or detent f², which projects through the said slot e' and engages one of three holes g' g² g³ on a flat extension h on the side of the cup, arranged in an arc which is concentric with the axis of said valve-stem. Thus when the valve-stem d is 55 turned to either one of the aforesaid three positions it will be held by the detent f² engaging the desired hole.

The grease cup or receptacle A is closed at its top by a cap J, the pendent flange J' of 60 which takes around the exterior side of the cup, and has an angle-slot j to engage with a pin j' on the cup. One or more of the slots and pins may be used. Thus the cap is secured, as will be readily understood. The 65 cap has on top a crown-piece or boss k provided with an elongated opening k' through which the plunger-stem L extends loosely. This stem is provided at its upper end with a suitable handle for convenience in manipulating the device, and at its lower end the stem is secured to the plunger L'. The stem thus moves loosely through the cap and may be turned slightly without moving the plunger. The upper portion of the plunger-stem 70 is flat or oval-shaped, as at m, corresponding to the shape of the opening k' in the cap, while the lower portion m' is round. Where the oval part and round part join is an annular shoulder n, the function of which will 75 be hereinafter stated. A helical compression-spring O surrounds the plunger-stem and bears against the plunger L' and forces the latter down. The top end of the spring is held by an annular rim p on the cap projecting into the spring, and the lower end of the spring is seated in a groove q on the top surface of the plunger. The face of the plunger is rounded or convex, as at v, to fit close against the concaved bottom v' of the 80 grease-cup. Thus the plunger can expel all the grease from the cup.

In order to apply the cap J and plunger L' to the receptacle A it is necessary to first compress the spring and hold it in a compressed condition. The spring is first compressed by forcing the cap down on the stem 85

L until the top of the crown *k* has passed below the shoulder *n*, and then the stem, through the medium of its handle, is given a quarter-turn to cause the widest part of the said shoulder to take crosswise of the elongated opening *k'*, as shown in Fig. 4, and thus the shoulder *n* takes upon the top of crown boss *k* and confines the cap low down on the stem, the spring being compressed. The cap may now be fitted over the cup *A* and secured thereto by first engaging the vertical portion of its angle-slot *j* with the pin *j'*, and then turning the cap to bring the said pin into the horizontal part of the slot. This being done the stem may then be given a quarter-turn to release the shoulder *m* and allow the stem to move loosely through the crown-opening *k'*. This release of the device which holds the spring compressed allows the spring to force 20 the plunger down upon the lubricant in the cup. By this construction and arrangement of the parts it will be seen that the plunger follows the lubricant as the latter feeds out throughout the passage *b* and exerts a constant pressure upon the same as long as any lubricant remains in the cup.

The plunger-stem *L* has a longitudinal passage *r* through it for the admission of air to the cup during the time of withdrawing the plunger, and a ball-valve *s* closes said passage during the time the spring is pressing the plunger on the grease. The ball-valve occupies a socket *t* in the plunger, which is closed by a screw-plug *u*, having an elongated passage *r'*. The socket has a valve-seat *r*² at the lower end of the passage *r*, which closes tight when the ball-valve *s* is in position shown in Fig. 2 and entirely closes the upward passage *r*. The valve cannot, however, 35 seat closely on the elongated passage *r'*, as

small openings will be left for passage of air downward through said passage to the cup during the time of withdrawing the plunger *L'*. By means of the passage *r* and valve *s*, when it is desired to withdraw the cap and 45 plunger from the cup *A*, air may enter the cup and prevent back suction of the lubricant, which suction would cause the lubricant to follow the plunger when withdrawing it from the cup.

It will be understood that when the lubricant is under pressure by action of the spring the ball-valve *s*, by seating on the upper seat *r*², prevents the lubricant from being forced out through the passage *r*.

Having thus described my invention, what I claim is—

A lubricator having, in combination, a cup or receptacle open at top and provided with an outlet passage; a cap closing the open top 60 of the cup and having an opening; a plunger-stem movable loosely in said opening and having an unoccupied air passage or round bore extending longitudinally; a plunger, *L'*, provided with a socket into which the lower 65 end of the plunger-stem fits; a screw-plug closing the lower end of the socket and having an opening; and a ball-valve occupying the said socket and adapted to open and close the said round bore in the stem but when 70 seated on the said screw-plug leaving small openings for downward passage of air to the cup, substantially as described.

In testimony whereof I affix my signature in the presence of two witnesses.

WILLIAM J. FERGUSON.
